UNITED STATES PATENT OFFICE

152,150

DESIGN FOR A TOY FIGURE

Marvin Glass, Chicago, Ill.

Application August 1, 1946, Serial No. 132,166

Term of patent 3½ years

(Cl. D34—15)

To all whom it may concern:

Be it known that I, Marvin Glass, a citizen of the United States, residing at Chicago, in the county of Cook and State of Illinois, have invented a new, original, and ornamental Design for a Toy Figure, of which the following is a specification, reference being had to the accompanying drawing, forming part thereof.

Fig. 1 is a front elevational view of a toy figure, showing my new design;

Fig. 2 is a rear elevational view;

Fig. 3 is a view from the right-hand side of the toy figure, shown in Fig. 1; and

Fig. 4 is a view from the left-hand side thereof.

I claim:

The ornamental design for a toy figure, as shown.

MARVIN GLASS.
